UNITED STATES PATENT OFFICE

2,602,526

BUILDING CONSTRUCTION

Hobart M. Day and George H. Urban,
Wausau, Wis.

Application April 19, 1949, Serial No. 88,454

1. Claim. (Cl. 189—34)

2

This invention relates to insulated building constructions, and more particularly it relates to metal building structures having means for retaining insulating material thereon.

More specifically the invention relates to a building structure comprising a plurality of metal plates fastened together by a plurality of spaced threaded bolts, clamp members retained on the spaced bolts and extending outwardly of the metal plates, insulating material positioned on the metal plates in flat face contact therewith, and means attached to the clamp members for retaining the insulating material on the metal plates.

Many unsuccessful attempts have been made previously for providing means to retain and support insulating material, such as mineral wool bats, in position on the inside surface of building structures made of plain or corrugated sheet metal, such as by adhering the bats by adhesive or by applying an outer retaining sheath. Such methods are costly, cumbersome and do not provide secure retaining means which will insure retention of the insulating material and permit removal of same when necessary, especially in the case of temporary metal building structures.

According to the present invention the retaining means for the insulating material are simple in construction and can be readily applied so as to securely retain the insulating material on the metal structural elements.

Other objects and advantages of the invention may be apparent to those skilled in the art from the following detailed description of what are now considered to be the preferred embodiments of the invention.

Referring to the drawings:

Figure 1 is a plan view of the interior surface of a metal building construction showing bats of insulating material retained thereon in accordance with the present invention.

Figure 2 is a sectional view taken on lines 2—2 of Figure 1.

Figure 3 is a view, partly in section, taken on lines 3—3 of Figure 2.

Figure 4 is a perspective view of one form of a clip member.

Figure 5 is a sectional view similar to Figure 2 showing the use of a modified clip construction.

Figure 6 is a perspective view of a modified clip member used in the construction of Figure 5, and

Figure 7 is a perspective view of a retaining element for retaining the insulating material.

Referring to the drawings, Figures 1 and 2 disclose a metal building construction made of

smooth or corrugated metal plates 10, fastened together by suitably spaced threaded bolts 11 at their overlapped marginal portions, and securely locked by nuts 12. In the usual metal building construction these bolts 11 extend toward the interior of the building construction. Clamp members 16 are provided having the construction shown in Figure 4 in order to retain the bats of insulating material 15 on the surface of the metal plates 10. These clamp members are made of flat flexible metal strips, preferably of steel, which are bent into the contour shown in Figure 4 so as to provide a reversely bent end consisting of U-shaped leg portions 18 and 17 and an upwardly extending member 21 having one or more spaced apertures 22 for a purpose to be explained later. The leg portions 18 and 17 are provided with aligned apertures 19 and 20, respectively, to permit the clamp member to be slipped over the free end of bolts 11, as shown in Figures 2 and 3. The leg members 17 and 18 are positioned at an acute angle to each other, less than 45°, and are slightly compressed or moved toward each other when applied to the bolt 11 so that when released the leg portions normally tend to spread apart. This resulting tension causes the inner perimeter of the apertures 19 and 20 to engage and wedge between the threads of the bolt 11 and thus firmly retain the clamp member 16 on the bolt 11.

As shown in Figures 1 and 2, a plurality of spaced clamp members 16 are positioned on the spaced bolts 11 used for fastening the metal sheets 10 of the building construction. Bats of insulating material 15 are then applied in flat face contact with the surfaces of the metal plates and a sufficient number of fastening members 25 are then inserted in the apertures 22 so as to extend between pairs of clamp members, as shown in Figures 1 and 2, to retain the insulating bats 15 on the metal plates 10. The retaining members 25 are made of stiff metal rods or wires having bent pointed ends 26 for facilitating their insertion into the apertures 22. It is to be understood that other retaining means for the insulating material may be used such as bands, wire, string, etc., which may be fastened to the clamp members in any suitable manner.

The invention is not restricted to the specific clamp member construction shown in Figure 4. For example, another suitable clamp member construction is shown in Figure 6 which is made of a flat metal strip bent upon itself to provide leg portions 30 and 31 which are provided with one or more aligned spaced apertures 32 at the upper end thereof, and bent inwardly at the lower

end thereof to form members 33 and 34 having alignable apertures 35 and 36, respectively. When this clamp member construction is used the leg portions 30 and 31 are brought together under tension so as to cause the inwardly bent members 33 and 34 to overlap in the position shown in Figure 5, and to align the apertures 35 and 36. The clamp member is then slipped over the threaded bolt 11 and released. The spring tension of the legs 30 and 31 will cause the peripheral surfaces of apertures 35 and 36 to engage and wedge between threads of bolt 11, thereby firmly retaining the clamp member on the bolt. A plurality of such clamp members are used to provide a sufficient number of spaced members for receiving retaining members 25 or other retaining means receiving in apertures 32 of the clamp members for retaining the insulating material securely on the metal plates 10.

It will be apparent from the foregoing description that a very efficient, economical and simple means is provided for retaining insulating material on metal building constructions. The clamp members and fastening elements can be applied by unskilled labor as no experience or training is required to perform the operation. No tools are necessary because the clamp members are applied manually by simply slipping them on the bolts and retaining elements are supplied of suitable dimensions so that they are simply inserted in the apertures of the clamp members. Bats of insulating material can then be applied very rapidly and with extremely little labor. The bats of insulating material are securely retained on the metal plates and will not sag or fall off. The bats can also be easily removed in event of needed dismantling of the structure because the fastening elements and clamp members can be readily removed manually without requiring any tools by simply disengaging the clamp from the bolt and slipping it off.

It is to be understood that numerous modifications and changes may be made in the present construction embodying the essential and significant features of this invention which are intended to be covered by the appended claim.

We claim:

A building structure comprising a plurality of metal plates fastened together by a plurality of spaced threaded bolts, said bolts extending beyond one face of said plates, spring clamp members frictionally retained on said spaced bolts and extending outwardly of said face of said metal plates, each of said spring clamp members comprising a metal strip reversely bent at one end thereof to provide U-shaped leg members, aligned apertures in said leg members frictionally engaging said bolts adjacent said metal plates, and the other end of said strip provided with retaining apertures for receiving wire rods therein, insulating material positioned on said metal plates in flat face contact with said face of said plates and covering said U-shaped leg members of said spring clamp members, and wire rods received in the retaining apertures of said clamp members and retaining the insulating material on said metal plates, said wire rods being of a length to extend between said spaced clamp members.
